CLAIM

(21) Appl. No.: **29/433,832**

The design for a softsided textile eyewear case with attached optical cloth flap, as shown and described.

(22) Filed: **Oct. 5, 2012**

DESCRIPTION

(51) **LOC (10) Cl.** **03-01**

FIG. 1 is a perspective view of the softsided textile eyewear case with attached optical cloth flap when the attached optical cloth flap is inside the case;

(52) **U.S. Cl.**

FIG. 2 is a top/open end view thereof;

USPC **D3/266**

FIG. 3 is a front and/or rear view thereof;

(58) **Field of Classification Search**

FIG. 4 is a side view thereof;

CPC A45C 11/04; A45C 11/005; A45C 13/005;
A45C 11/043; A45F 2200/0541; B65D
2585/545; A61L 12/086; A47F 7/021; A47G
29/08; B60R 7/082

FIG. 5 is a bottom/closed end view thereof;

USPC D3/218, 219, 215, 224, 226, 263–266,
D3/230, 233; 206/5, 5.1, 6; 224/908;
248/902

FIG. 6 is an alternate perspective view thereof showing the usage configuration with the attached optical cloth flap exposed;

See application file for complete search history.

FIG. 7 is an alternate top/open end view thereof;

(56)
